MATCH BOOK BRACE

Henri Daniel, New York, N. Y.

Application December 11, 1940, Serial No. 369,536

5 Claims. (Cl. 206—29)

This invention relates to new and useful improvements in a match book brace.

The invention particularly proposes a brace adapted to be used in combination with a book of matches having a wire stitch mounted through and holding the bottom portions of the cover and match sheets together. The invention contemplates characterizing the brace by the fact that it is constructed from a V-shaped strip of rigid material of a length substantially equal to the width of said book of matches, and adapted to be mounted on the bottom portion thereof so as to have its arms extending over the front and back portions of the wire stitch. It is proposed to construct the arm portions of the V-shaped strip with inturned edge portions engaging over the front and back portions of the wire stitch for holding the V-shaped strip thereon.

It is proposed that the said V-shaped strip be constructed of sheet metal, composition, or other rigid materials. It is contemplated to imprint, engrave or in other way decorate the outside faces of the strip with ornamentation or with individuals' initials, or other attractive material or advertising.

A dominating feature of the brace resides in the fact that it extends over and covers the wire stitch, which is not very ornamental. Moreover, it protects one's clothing from being pierced by the pointed ends of the wire stitch. Furthermore, the brace firmly secures together the bottom portions of the book of matches preventing the cover, or portions thereof, being accidentally torn away from the wire stitch. Moreover in those books of matches having match striking material on the bottom portion thereof, the brace will extend forwards of the striking material and protect it from being worn away, or soiled with wet fingers, etc.

Still further the invention contemplates a modification in which resilient means is mounted within the V-shaped strip, and engages the bottom edge of the book of matches urging the V-shaped strip and book of matches apart to firmly urge the wire stitch against the inturned edge portions of the V-shaped strip.

Another object of the invention is the construction of a device as described which is simple and durable and which may be manufactured and sold at a reasonable cost.

For further comprehension of the invention, and of the objects and advantages thereof, reference will be had to the following description and accompanying drawings, and to the appended claims in which the various novel fea-

tures of the invention are more particularly set forth.

In the accompanying drawing forming a material part of this disclosure:

Fig. 1 is a perspective view of a match book provided with a brace constructed in accordance with this invention.

Fig. 2 is a fragmentary enlarged edge elevational view of Fig. 1.

Fig. 3 is a horizontal sectional view taken on the line 3—3 of Fig. 2.

Fig. 4 is a front elevational view of a book of matches with a brace mounted thereon constructed in accordance with a modified form of this invention.

Fig. 5 is a longitudinal vertical sectional view of the book match brace shown in Fig. 4.

Fig. 6 is a transverse vertical sectional view as though taken on the line 6—6 of Fig. 5.

The match book brace, in accordance with this invention, is used in combination with a book of matches 10 having a wire stitch 11 mounted through and holding the bottom portions of the cover 12 and match sheets 13 together. The cover 12 has a bottom front flap 12a which continues into back section 12b, which continues into the front cover section 12c. The bottom edge of the front cover section 12c engages behind the bottom front flap 12a when the book of matches is closed. Match striking material 14 is mounted on the outer face of the bottom front flap 12a.

The brace, in accordance with this invention, comprises a V-strip of rigid material 15 of a length substantially equal to the width of the book of matches 10 and mounted on the bottom portion thereof with its arms 15a extending over the front and back portions of the book of matches, and over the front and back portions 11a and 11b, respectively, of the wire stitch 11. Inturned edge portions 16 are formed on the edges of the arms of the V-shaped strip 15 engaging over the front and back portions 11a and 11b of the said wire stitch 11 for holding the V-shaped strip 15 thereon.

The V-shaped strip 15 may be made of sheet metal, composition material, stiff paper, and other similar material. Preferably gold plated sheet metal should be used, or other precious metals so that the brace may be of a permanent character. It then may be removed from one book of matches when the book is consumed, and placed on another. The outer faces of the arms of the V-shaped strip 15 may be suitably decorated, or imprinted, or engraved with one's ini-

tials, or with advertising material, to enhance its permanent character. The brace may be removed from the book of matches by forcing it laterally in one direction or the other so that it slips off from one or the other sides of the book of matches.

In Figs. 4 to 6 inclusive, a modified form of the invention has been disclosed which distinguishes from the prior form in the fact that resilient means has been associated with the V-shaped strip 15 so as to engage the bottom edge portion of the book of matches 10 urging the strip and book of matches part so as to firmly engage the inturned edge portions 16 against the wire stitch 11. This resilient means comprises a leaf spring 19 having a central upwardly projecting portion 19a with inclined sides. The ends of the leaf spring 19 extend along the center of the V-shaped strip 15 and slidably engage beneath a pair of inturned lugs 17, preferably formed from the material from which the strip 15 is made.

In other respects this form of the invention is identical to the previous form and like parts are identified by like reference numerals.

The operation of this form of the invention may best be understood by examining Fig. 4 and noting that the brace may be removed by forcing it laterally in one direction, or the other, so that it slips off from the book of matches. The brace may then be engaged on another book of matches and properly fit this book of matches irrespective of the fact that the wire staple 11 thereof may be in a different vertical position. The leaf spring 19 will compensate for such different positions. In each case the central projecting portion 19a will engage the bottom of the book of matches forcing the brace downwards so that the inturned edges 16 engage the wire stitch 11.

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. In combination with a book of matches having a wire stitch mounted through and holding the bottom portions of the cover and match sheets thereof together, a match book brace, comprising a V-shaped strip of rigid material of a length substantially equal to the width of said book of matches and mounted on the bottom portion thereof with its arm extending over the front and back portions of said wire stitch, and inturned edge portion on the edges of the arms of said V-shaped strip engaging over the front and back portions of said wire stitch for holding the V-shaped strip thereon.

2. In combination with a book of matches having a wire stitch mounted through and holding the bottom portions of the cover and match sheets thereof together, a match book brace, comprising a V-shaped strip of rigid material of a length substantially equal to the width of said book of matches and mounted on the bottom portion thereof with its arm extending over the front and back portions of said wire stitch, inturned edge portion on the edges of the arms of said V-shaped strip engaging over the front

5 and back portions of said wire stitch for holding the V-shaped strip thereon, and resilient means mounted within said V-shaped strip and engaging the bottom edge of said book of matches and urging said wire stitch against said inturned edge portions.

3. In combination with a book of matches having a wire stitch mounted through and holding the bottom portions of the cover and match sheets thereof together, a match book brace, comprising a V-shaped strip of rigid material of a length substantially equal to the width of said book of matches and mounted on the bottom portion thereof with its arm extending over the front and back portions of said wire stitch, in-turned edge portion on the edges of the arms of said V-shaped strip engaging over the front and back portions of said wire stitch for holding the V-shaped strip thereon, and resilient means mounted within said V-shaped strip and engaging the bottom edge of said book of matches and urging said wire stitch against said inturned edge portions, comprising a leaf spring mounted within said V-shaped strip along the bottom portion thereof.

4. In combination with a book of matches having a wire stitch mounted through and holding the bottom portions of the cover and match sheets thereof together, a match book brace, comprising a V-shaped strip of rigid material of a length substantially equal to the width of said book of matches and mounted on the bottom portion thereof with its arm extending over the front and back portions of said wire stitch, in-turned edge portion on the edges of the arms of said V-shaped strip engaging over the front and back portions of said wire stitch for holding the V-shaped strip thereon, and resilient means mounted within said V-shaped strip and engaging the bottom edge of said book of matches and urging said wire stitch against said inturned edge portions, comprising a leaf spring mounted within said V-shaped strip along the bottom portion thereof, and having an upwardly projecting section engaging the bottom edge of said book of matches.

5. In combination with a book of matches having a wire stitch mounted through and holding the bottom portions of the cover and match sheets thereof together, a match book brace, comprising a V-shaped strip of rigid material of a length substantially equal to the width of said book of matches and mounted on the bottom portion thereof with its arm extending over the front and back portions of said wire stitch, in-turned edge portion on the edges of the arms of said V-shaped strip engaging over the front and back portions of said wire stitch for holding the V-shaped strip thereon, and resilient means mounted within said V-shaped strip and engaging the bottom edge of said book of matches and urging said wire stitch against said inturned edge portion, comprising a leaf spring mounted within said V-shaped strip along the bottom portion thereof, and having an upwardly projecting section engaging the bottom edge of said book of matches, said strip of material having lug portions bent inwards from the bottom sides thereof, and the ends of said leaf spring being slidably engaged beneath said lug portions.
